RELAY

Rolf Hofgaard, Nordstrandshogda, near Oslo,
NorwayApplication December 4, 1946, Serial No. 714,070
In Norway April 29, 1946

5 Claims. (Cl. 200—1)

1

The present invention relates to a relay of the type which serves to simultaneously close or interrupt a large number of contacts for electrical circuits.

Relays of this type are utilized in a number of different cases such as for instance in electrical calculating machines, signal devices of various kind etc.

The object of the invention is to provide a relay of this type in which the movement of a number of elastic contact arms from a resting position to a working position is caused by means of a mechanically operated actuating member, whereas the connection between this member and the contacts, i. e. the possibility of closing and interrupting the circuits, is controlled by means of an electro-magnet which, as it has only a very small mechanical work to perform, may be given very small dimensions.

In accordance with the invention the mechanically operated actuating member and the electro-magnet control member cooperate in such a manner that the mechanically operated actuating member is caused to engage the contact arms when these are in their position of rest, and the electro-magnet is energized, whereby the contact arms against spring action are transferred to working position and are locked in this position irrespective of whether the electro-magnet is still energized or not, whereas the mechanically operated actuating member, in case the contacts are locked in working position and the electro-magnet is not under current, is permitted to release the locking means so as to liberate the contact arms and allow same to move back to their position of rest under spring action.

In the preferred embodiment of the invention there is used a mechanically operated reciprocating actuating member which is coupled with the elastic contact arms by means of an electro-magnetic operated spring actuated hook. This hook acts in such a manner that after energization of the electro-magnet it will first lift a pivoted arm connected with the elastic contact arms so that a part of this arm is placed in the path of the reciprocating member which will then move the contact arms against spring action slightly further than their working position, whereupon at the beginning of the return movement of the contacts, a nose on said pivoted arm engages said hook so as to lock the contacts in their working position and maintain them in that position, irrespective of whether the electro-magnet is still energized or not, until the reciprocating member at the moment when the electro-magnet is not

2

energized will again move the contacts a short distance away from their working position so as to disengage the pivoted arm from the spring actuated hook and allow the hook and the arm 5 to move back to their original position, whereupon the spring actuated contact arms which are then liberated swing back to their position of rest.

In the accompanying drawing a form of the invention is illustrated, in which:

Figure 1 is a side view of the contact relay with the elastic contact arms in position of rest and the electro-magnet de-energized.

Figure 2 is a similar view of the contact relay 15 with the elastic contact arms still in their position of rest and with the electro-magnet energized.

Figure 3 is a similar view of the contact relay with the elastic contact arms in working position.

20 The contact relay comprises a number of elastic contact arms arranged in pairs as indicated with the numbers 1 and 2, these arms being secured at their lower ends in an insulating block 3 and interconnected at their upper ends by 25 means of another insulating block 4.

Between each pair of contact arms 1 and 2 there is located elastic contact arms 5 which are also secured to the block 3, but the upper ends of which are free.

30 Contact arms 5 are provided with contacts as indicated at 6, these contacts in their resting position (Figures 1 and 2) engaging one contact arm (left) in the pair of contact arms between the members of which they are located, whereas 35 in the working position, as indicated on Figure 3, they engage the other (right) contact arm in the same pair of contact arms 1, 2 etc. being then bent sidewise.

In the block 4 is pivotally mounted an arm 7 which is provided on its underside with a projection or nose 8.

9 is an electro-magnet, the armature 10 of which is in the form of a two-armed lever pivoted about pin 11. The part of armature 10 which is 45 further away from the magnet is made in the form of a hook 12 extending towards the underside of the pivoted arm 7. 13 indicates a mechanically operated reciprocating actuating member which serves to move the contact arms from resting position to working position and to release them again by engagement with the pivoted arm 7 on block 4.

In the position illustrated in Figure 1, in which the electro-magnet is not energized, the arm 7 is not energized by the reciprocating actuating

member, but when the electro-magnet is energized the arm 7 is lifted by the hook 12, as indicated in Figure 2, and the reciprocating actuating member 13 will then move the arm with the block and the elastic contact arms towards the left, so that they are brought into the position indicated on Figure 3. Contacts are then closed between the free contact arms 5 and the right-hand contact arms in each of the pairs of contact arms 1 and 2. This position is called the working position of the relay.

When the arm 7 is moved towards the left by means of actuating member 13, the nose 8 passes the hook 12 and the pivoted members 7 and 12 will then interlock, so that the relay remains in this working position, even if the electro-magnet is energized, until actuating member 13 again engages arm 7 during its next stroke.

If on that occasion the electro-magnet is still energized the contact relay will remain in working position as the nose 8 is only moved a slight distance away from the hook 12 which remains in position and engages the nose again as soon as actuating member 13 has started its movement towards the right.

However, if the electro-magnet is de-energized when the contact relay is in working position, as indicated on Figure 3, and the actuating member 13 then moves the arm 7 towards the left the armature 10 with the hook 12 returns to the position illustrated in Figure 1, and the contact relay under spring action will then return to the resting position, the various parts taking up the position illustrated in Figure 1.

In the form illustrated in the drawing the armature 10 is provided with a depending arm 14 engaging an auxiliary contact spring 15.

This contact spring on the one hand serves the purpose of moving the pivoted armature towards the position indicated in Figure 1, and on the other hand may also cooperate with another contact spring 16 which may for instance operate as a self-closing circuit contact for the electro-magnet in cases when this is desired.

By the use of the contact relay herein described in electrical calculating machines a smaller or larger number of contact relays of the type illustrated in the drawing may be placed in a row and be adapted to be cut in or out by means of a common mechanical actuating member such as for instance a reciprocating rod or shaft with arms or projections corresponding to the element 13 indicated in the drawing. The cutting in and out of the individual relays then takes place by means of current impulses to the electro-magnet of each relay, and these current impulses in a known manner may be controlled by means of relays which have been brought into working position during the preceding stroke of the mechanical actuating member.

I claim:

1. A contact relay comprising a plurality of

interleaved sets of relatively stationary and relatively movable resilient contact arms, an insulating block connecting the ends of the relatively movable contact arms to each other, said movable contact arms being biased toward a rest position, a mechanically reciprocated actuating member movable in spaced relation to said insulating block, a normally-inoperative coupling member movable into operative position in the path of travel of said actuating member to transmit motion therefrom to move said movable contact arms into working position, an electromagnet having an armature operative in its attracted position on energization of the electromagnet to displace said coupling member into operative position, and cooperating latch means on said coupling member and armature for retaining said movable contact arms in working position and said armature in attracted position upon movement of said mechanically reciprocated actuating member away from said coupling member.

2. A contact relay as recited in claim 1, wherein said cooperating latch means are relatively positioned to engage upon initial movement of the coupling member by resilient contact arms upon reversal of the direction of movement of said actuating member after its movement of the movable contact arms into working position, whereby said cooperating latch means are momentarily released upon successive movements of said coupling member into an end position by said actuating member.

3. A contact relay as recited in claim 2, wherein said armature is biased towards non-attracted position and said coupling member is biased toward inoperative position, whereby said armature separates from said coupling member upon the momentary release of said latch means when said electromagnet is de-energized and said coupling member then moves into inoperative position upon separation of said actuating member therefrom.

4. A contact relay as recited in claim 3, wherein said coupling member is pivoted upon said insulating block and is gravity-actuated into inoperative position, and said armature has an arm positioned beneath said coupling member for lifting the same upon movement of the armature to attracted position.

5. A contact relay as recited in claim 4, wherein said latch means comprises the end of said armature arm and a projection on the lower face of said coupling member.

ROLF HOFGAARD.
